UNITED STATES PATENT OFFICE.

ERNEST ALFRED WOOTTON, OF MAYNOOTH, ONTARIO, CANADA.

SHEAF SHOCKER.

Application filed September 20, 1926. Serial No. 136,703.

This invention relates to improvements in stooking machines, with the principal object of providing a mechanical device which may be secured in a suitable manner to a binder 5 for the stooking of grain.

A further object is to provide a stooking device of this character which may be attached to binders already in existence without incurring a great deal of expense.

10 A still further object is to provide an improved device of this character which operates automatically when a predetermined number of sheaves have been delivered thereto. A yet further object is to provide a machine of 15 this character which may be used effectively on either a right or left hand cut binder.

With the foregoing and other objects in view, the invention consists essentially of a frame attached to the binder upon which is 20 mounted a conveyor, a hopper and a grain stooking basket whereby the grain as received from the binder is carried to the hopper and, when a predetermined number of sheaves have been received in the hopper, they 25 are automatically released and discharged into the stooking basket which, through automatic mechanical means, causes the grain to be placed on the ground in stook formation.

Referring now to the drawings in which 30 like characters of reference indicate corresponding parts in each figure:

Figure 1 is an elevation of my improved stooking device as seen from the rear and in a loading position.

35 Figure 2 is a plan view of the same.

Figure 3 is an end elevation of the machine in loading position ready for the rearward movement.

Figure 4 is a plan view with the elevator 40 hopper and basket removed.

Figure 5 is a detail in elevation illustrating the sheaf-carrying basket and mechanism.

Figure 6 is a plan view showing the sheaf-carrying basket in the extreme rear position 45 prior to the release of the sheaves.

Figure 7 is a sectional detail of the release mechanism for the basket bottom.

Figure 8 is a detail of the support for the front end of the basket while in a vertical 50 position.

Figure 9 is a detail of the guide rod which is associated with the operation of the basket bottom.

Figure 10 is a view of the elevator mecha- 55 nism with the elevating member removed.

Figure 11 is a detail of the horizontal track construction, and

Figure 12 is a detail view of the gears employed to operate the basket.

Figures 13 and 14 are details of the spiral 60 reversing shaft with carriage arm attached thereto.

Referring now to the drawings which disclose a preferred embodiment of my invention, A represents the shocker as a whole comprising in the main the elevator, the hopper and the sheaf-carrying basket, indicated by the letters A, B, and C respectively. 65

As particularly illustrated in Figure 1, the improved device is carried by the frame 10 which is secured in any well known manner to the frame of the binder D. In the ordinary operation of the binder the grain is cut and conveyed to the binder deck E where it is tied in sheaves or bundles and discharged 70 therefrom by mechanism well known in the art. The sheaf, on being discharged from the binder deck, is received by the conveyor A when it is carried upwardly and discharged 75 into the hopper B. The elevator construction shown here comprises the sprockets 12 and 13 mounted on the shafts 14 and 15 which are supported by the frame 16 and connected by the chains 17 and 18, the conveyor member 11 being secured to the link members of 80 the chains. A feature of the elevator is the fact that it is designed to operate in a reciprocatory movement. For this purpose the gears 12 are loosely mounted on the shaft 14 (see Figure 10) while the sliding clutch member 19 is keyed thereto. The link 20 is connected to the bell-crank lever 21 which is in turn connected to the clutch member 19 and to the lever 22 which is pivotally mounted in the bracket 23. The upper extremity of the 85 lever 22 is designed to be engaged by the pin 24 mounted on the gear 25, the operation of which will be hereinafter more fully explained.

90 Mounted adjacent the elevator is a hopper B. This hopper is supported on the frame in any well known manner, and is designed to retain a predetermined number of sheaves and, through automatically timed mechanism, discharge the sheaves into the basket C. 95 The hopper is substantially V-shaped in formation, and is provided with a door 26 pivotally mounted at 27 and held in closed position by the spring latch members 28.

100 Situated adjacent the lower or discharge 110

opening of the hopper and directly therebelow is the sheaf-carrying basket C. This basket is designed to receive the sheaves discharged from the hopper B, after which they are carried to a vertical position to be discharged on the ground in shock formation. The construction of this member comprises a frustro-conical shaped basket 29, the base of which is supported by the fixedly mounted 10 arm or supporting member 30 pivotally and turnably connected at 31 and 32 to the shaft 33, upon which is mounted the bevelled gear 34 (see Figure 5).

The basket, on assuming a vertical position and prior to forming a stool, is designed to travel rearwardly and forwardly through the operation of suitable mechanism. For this purpose the basket is mounted on a carriage 35 provided with wheels 36 which are 20 designed to travel on the tracks or guideways 37 and 38. The wheels 39 mounted in a horizontal plane adjacent the wheels 36 are adapted to act as anti-friction rollers and effect a smooth working action when the carriage 25 is in operation. Secured to the basket member substantially midway thereof is a secondary supporting arm 40 upon the free end of which is rotatably mounted the grooved rollers 41. These rollers are adapted 30 to travel on the curved and inclined track or guide rail 42 which is supported by the frame with suitable brace members.

Releasably mounted adjacent the base of the basket and designed to fit into the semi-circular slot 43 is the plate 44 forming the base or bottom of the basket, while substantially midway of the basket are operatively connected the sheaf-retaining fingers 45 and 46 (see Figure 5). As will be hereinafter 40 more fully referred to, the fingers 44, as particularly illustrated in Figure 3, are in normal open position. As the basket travels up the curved inclined track 42 the latch members 47 and 48 are engaged and tripped by the projecting arm 49 mounted on the track (see Figure 1). This action causes the springs 50 to pull the fingers 45 and 46 (see Figures 5 and 6) in a manner so as to nearly 50 span the open side of the basket 29. In this way the sheaves are held in stool formation while the basket is in a vertical position. The fingers 45 and 46 are designed to operate in a lateral direction, and for this purpose are mounted in housings 51 secured to 55 the basket. The pulleys 52 connected to the fingers 45 and 46 are designed to be engaged by a chain or cable 53 travelling over the pulleys 54, 55 and 56 on the basket, one end of the chain being secured to the member 44 as at 57, while the other end is secured to the coil spring 58 enclosed in the housing 59 which is also secured to the basket.

The operation of the basket is designed to be automatic, and the mechanism for this 65 purpose comprises the shaft 60 connected by

the chain 61 to the sprocket 62 which is mounted on the shaft 14. It might be well to state here that the shaft 14 rotates continuously, while the binder is in motion, and the several mechanisms which will be further 70 described are adapted to automatically engage and disengage and thereby effect the operation of the various elements.

The lever member 63 (see Figures 1 and 4) is pivotally mounted at 64 and connected by 75 the link member 65 to the substantially L-shaped lever 66 which in operation causes the sliding gear 67 to engage the mutilated gear 68 mounted on the shaft 69. The sprocket 70 also mounted on this shaft is 80 connected by the chain 71 to the sprocket wheel 72 in turn mounted on the shaft 73. The bevelled gear 74 is keyed to this shaft, and it is through this gear, which meshes 85 with the bevelled gear 34, that power is delivered to carry the basket from a horizontal to a vertical position. The means for restoring the basket from the vertical to the horizontal comprises the mutilated gear 75 and the full gear 76, the latter of which is mounted 90 on the shaft 69, the gear 75 referred to effecting the reversal of rotation of the shaft 69 and consequently that of the shaft 73, the lever 77, through automatic means later referred to, effecting the necessary reversal. 95

During the stooking operation, the carriage 35 will move rearwardly and at a predetermined point discharge the sheaves in stool formation. The means for effecting this operation include the sprocket 78 mounted on the shaft 14 and connected by the chain 79 to the sprocket 80 which is keyed to the shaft 81. The sliding clutch member 82 is designed to engage and disengage the loosely mounted sprocket 83 which is connected by 105 the chain 84 to the sprocket 85 mounted on the shaft 86 which is in the form of a reversing spiral. The carriage 35, through the arms 87 and bearing 88, is connected to this shaft 86 and it is through the operation of 110 this shaft that the carriage is moved in a rearward and forward direction. The means effecting the engagement of the member 82 comprise the lever 89 pivotally mounted at 90 and connected by the link 91 to the bell-crank 92 which is pivotally mounted on the member 82, while the disengaging means comprise the lever member 93 pivotally mounted at 94 and also pivotally connected 115 to the member 82.

In operation, and after the sheaves have been discharged from the binder deck E, as previously described, they are deposited on the conveyor 11. At this point, the rotation of the gear 25 operating the discharge arm 125 will cause the pin 24 to engage the upper extremity of the lever 22, tripping the same and causing the clutch member 19, through the link 20 and lever 21, to mesh with the gear 12 causing the member 11 to move upwardly 130

until, as indicated in dotted lines, the member reaches a substantially vertical position at the top of the sprocket 13. Mounted on the downward moving side of the endless chain 18 is a substantially V-shaped trip member 95 which is adapted to engage the disc member 96 of the clutch 19 so that, on the completion of the upward movement of the member 11, the member 95 will engage the member 96 and automatically cause the clutch 19 to disengage. During the upward movement of the member 11 the spring 97 will have been tensioned and upon the disengagement of the clutch 19 the spring 97 will act to 10 store the member 11 to normal position, as illustrated in Figure 1. The reciprocal movement just described will, through the sprocket 98 and chain 99, cause the sprocket 100 to make a partial revolution. This 15 sprocket, mounted on the shaft 101, is connected by the chain 102 to the sprocket 103. Mounted on this chain is a lever engaging dog or projection 104 which will, after a series of operations of the member 11, make a 20 complete revolution. Therefore, when a predetermined number of sheaves have been delivered to the hopper B, the member 104 will engage and trip the curved portion 105 of the latch 28, thereby releasing the door 26 and permitting the sheaves by their own 25 weight to slide into the basket C, after which the action of the spring 106 will cause the door 26 to close. The forward movement of the chain 102 will cause the engaging member 104 to engage the lever 63 which, through the link and lever 65 and 66 respectively, causes the gear 67 to mesh with the gear 68 and, through the sprockets 70 and 72 previously described, rotate the shaft 73, and, 30 through the gears 74 and 83, cause the rotation of the shaft 34. The basket C at this point, through the operation of the gear 34, is caused to move upwardly, the rollers 41 on the arm 40 travelling on the curved and inclined track 42. As the basket moves upwardly the projecting arm 49 will engage first the latch member 47 and then the latch 48. The release of the latch members permits the fingers 45 and 46 to almost completely span 35 the open side of the basket C, this operation, of course, taking place before the basket has assumed a vertical position. Upon the basket reaching a vertical position, the untoothed portion of the gear 68 will have reached engagement with the toothed portion of the gear 67. The gear 67 will therefore, through the action of the spring 107, be restored to a normal position, the rollers 41 will be disengaged from the trackway 42, and the carriage 40 35 ready for rearward movement.

The front end of the basket is supported by lugs 108. The forward movement of the chain 102 will cause the member 104 to engage the lever 89 which will, through the link 91 and lever 92, cause the clutch member 82

to engage the gear 83, which, through the chain 84, causes the shaft 86 to rotate. The rotation of the shaft 86 moves the basket, which is mounted on the carriage, in a rearward direction. The principle in having the carriage moved rearwardly is to overcome the forward speed of the binder so that the stock, during discharge and formation, will be stabilized. As the carriage reaches the extremity of its rearward movement, the fingers 109 to which are attached the springs 110, engage projections 111 on the member 44, so that on reaching the rearward position the springs, as indicated in Figure 6, have been expanded. The engaging arms 112 at 45 this juncture engage the trip members 113, causing the member 44 to be released. On the release of this member it shoots backward and is supported by the rods 114. Simultaneous with the forward movement of the member 44 the chain 115 is tensioned which, through the action of the pulleys 54, 55, 52 and 56, causes the fingers 45 and 46 to resume their normal position and at the same time permit the sheaves to drop in stock 50 formation. The continued rotation of the shaft 86 will reverse the direction of movement of the carriage, and the carriage will therefore be returned to the extreme forward position as illustrated in Figure 5. Upon reaching the forward extremity the bearing 88 will engage the stop 116 which is connected to the lever 93 to cause the clutch member 82 to be disengaged.

During the forward travel of the basket, the member 44 slides back into the slot 43 and is locked therein by the latch member 112. The completion of the rearward movement of the carriage 35 will cause the arm 117 to engage the arm 118, to which is connected the lever 77 and through which the gear 67 is caused to mesh with the gear 75 which, meshing with the gear 76, transmits power to the shaft 69 and, through the previously described means and the shaft 23, to the gear 34 when the basket travels down the curved trackway 42 to assume normal loading position. The guide rod 119 illustrated in Figure 9 is designed to equalize the movement of the arms 109 during tensioning or releasing 60 of the springs 110.

It should be noted with respect to the automatic operation of the sheaf shocker that suitable means such as a clutch operable from the driver's seat, could be used to disengage the operating mechanism, so that in case, for example a small field of grain is encountered the stock will not be deposited in an obstructed position.

As many changes could be made in the above construction and many apparently widely different embodiments of my invention, within the scope of the claims, constructed without departing from the spirit or scope thereof, it is intended that all matter

contained in the accompanying specification and drawings shall be interpreted as illustrative and not in a limiting sense.

What I claim is:

5. 1. In a sheaf shocker and in combination, an elevator, a hopper timed from and thrown into gear by the elevator, a turnably mounted and slidably supported sheaf carrying basket timed from and thrown into gear by the hopper, and mechanism for causing the basket to assume a vertical position and to travel rearwardly, means for automatically causing the basket at a predetermined point in its rearward travel to discharge the shock,
- 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935
2. In a sheaf shocker and in combination, an elevator, means for imparting a reciprocatory movement to the elevator, a hopper timed from and thrown into gear by the elevator on a predetermined number of sheaves being received therein, a slidably supported, turnably mounted sheaf carrying basket, mechanism timed from the hopper for automatically operating the basket on a predetermined number of sheaves being delivered thereto, means for causing the basket to assume a vertical position and for moving the basket rearwardly to shock-discharging position and forwardly to return to normal loading position, and means for causing the basket at a predetermined point in its rearward travel to discharge the shock.
3. The invention according to claim 1, in which a curved and inclined track is provided, and supporting arms provided with rollers for the basket and adapted to engage with said track.
4. The invention according to claim 1 in which the basket is pivotally and turnably mounted on a carriage provided with wheels to travel backwardly and forwardly on suitable guideways.
5. In a sheaf shocker of the character described the combination with an elevator, of a hopper timed from and thrown into gear by the elevator on a predetermined number of sheaves being received, a turnably mounted horizontally movable sheaf receiving and shock depositing basket, horizontally arranged tracks for the basket, mechanism for causing the basket to assume a vertical position and mechanism associated with the aforementioned track for engaging with the basket when assuming a vertical unloading position.
6. In a sheaf shocker, the combination with a pivotally mounted horizontally and vertically movable sheaf receiving basket, a hopper timed from and thrown into gear by the elevator and intermediate of the basket and the elevator, mechanism timed from and

thrown into gear by the hopper for operating the basket vertically, backwardly and rearwardly, and comprising spring actuated doors for the hopper, and spring actuated latch means for normally holding the door in closed position, means for releasing the latch means and means associated with the latch operating means to cause the basket to move from a vertical to a horizontal position.

7. The invention according to claim 1, characterized by the fact that finger members are provided on the basket to automatically engage with a portion thereof.

8. In a sheaf shocker and in combination, a reciprocatory elevator, a hopper, and a sheaf receiving basket, means in combination with the discharge of the sheaf from the binder causing the elevator to operate, means in combination with the elevator for operating the hopper, automatic means adapted to move the basket from a normal horizontal position to a vertical position and means associated with the basket adapted to move the basket rearwardly in a vertical position then forwardly in a vertical position and finally to a horizontal position.

9. In a device of the character described, comprising in combination an elevator and a sheaf receiving hopper, means associated with the elevator, means adapted to operate the hopper, releasing means when a predetermined number of sheaves have been received therein.

10. In a sheaf shocker and in combination, a sheaf receiving basket adapted to travel rearwardly and forwardly on a horizontal trackway, means for causing the basket to move rearwardly and then forwardly and means for automatically disengaging the operating means.

11. In a sheaf shocker and in combination, a sheaf receiving basket adapted to move rearwardly and forwardly in a vertical plane, releasable means for supporting the sheaves in the basket and means operable upon the extremity of the rearward movement whereby the sheaf supporting and retaining means are simultaneously released to permit the sheaves to be discharged on the ground in shock formation.

12. In a sheaf shocker and in combination with a sheaf receiving basket, a curved inclined trackway and a horizontal trackway, means for causing the basket to move from a horizontal to a vertical position, means for causing the basket to travel rearwardly then forwardly, and automatic reversing means to move from a vertical to a horizontal position.

In witness whereof I have hereunto set my hand.

ERNEST ALFRED WOOTTON.
